UNITED STATES PATENT OFFICE.

JOHN S. CARPENTER, OF IRVINGTON, NEW JERSEY, ASSIGNOR TO WORTHINGTON PUMP AND MACHINERY CORPORATION, OF NEW YORK, N. Y., A CORPORATION OF VIRGINIA.

HYDRAULIC TURBINE.

Application filed September 21, 1921. Serial No. 502,268.

To all whom it may concern:

Be it known that I, JOHN S. CARPENTER, a citizen of the United States, residing at Irvington, county of Essex, and State of New Jersey, have invented certain new and useful Improvements in Hydraulic Turbines, fully described and represented in the following specification and the accompanying drawings, forming a part of the same.

10 This invention relates to improvements in hydraulic turbines and particularly to high speed turbines.

It has been common heretofore to provide mixed flow turbines having outer bands and 15 crowns, wherein the water guiding or inner surface of the outer band was flared outwardly in the direction of the water flow, but in such cases generally the outward flare was either too great for the normal speed 20 for which the runner was designed, or was too small a slope for a high speed runner. Where in a few exceptional cases the angle of the outward flare was proper for the normal speed of the turbine, there was either no 25 inner band or it was either straight,—that is, had no flare,—or was flared the wrong way, namely, with a slope toward the axis of the runner in the direction of the water flow. I have discovered that with such runners there are appreciable losses due to 30 eddies or whirls. The object of my invention is to provide a runner in which these losses will be avoided.

With this object in view the invention consists in a hydraulic turbine having a runner 35 provided with an inner as well as an outer band whose water guiding surfaces are sloped outward in the direction of the water-flow, and having the angle of slope so related to 40 the normal speed of the runner that no eddies are formed, as will be more fully explained hereinafter.

The invention will first be described in connection with the accompanying drawings 45 and then more particularly pointed out in the claims.

In the drawings,—

Fig. 1 is a vertical section through one 50 form of hydraulic turbine embodying the invention; and

Fig. 2 is a half plan partly in section of the same.

Referring to the drawings, the runner comprises the blades A, the outer band B 55 and the inner band C suitably mounted for

rotation. In the present example the runner has a hub D which is advantageously formed integral with the inner band, this hub being mounted on a turbine shaft E which is suitably hung from a suitable suspension bearing (not shown) and journaled in a bearing carried by the casing, as indicated at 1. The casing is arranged to conduct the water to the runner in the general direction of the axis of the runner. In the present example the water enters in a radial direction and then is deflected by the casing so as to flow in the axial direction when it strikes the runner. The casing shown comprises an annular cover-plate F and a co-70 noidal crown-plate G supported by the cover plate. The latter is carried by suitable supports from a bottom plate H. In the present example the supports comprise column bolts I. Suitable gates are provided for 75 controlling the water. These are indicated at K and in the best form of the invention are arranged so that their inner ends, when the gates are open, overhang the runner, as will be clear from the drawings. The over-80 hanging corners have their sides formed as stream line surfaces in the direction of the water flow downward, as, for example, by beveling or gradually reducing the thickness of the corner.

Any suitable gate-operating mechanism may be employed. In the present example, the gate spindle k is provided with an arm L connected by a link l to a ring M angularly movable on an upward projecting hub 90 N carried by the casing.

Beneath the runner is a curb-ring P which is provided with an upward-extending portion p flanged at its upper part, this flanged portion serving to support the interior part 95 of the bottom ring. The curb-ring P is carried by the foundation.

A draft tube R of annular form is joined to the curb-ring, the profiles of the sides sloping away from each other as shown in 100 the drawing. It is advantageous, however, to give the interior wall of the draft tube a greater slope than the outer wall.

A most important feature of the invention is the provision of proper profiles for the 105 water-guiding surfaces of the inner and outer bands of the runner. If the outward slope of the profiles of these bands is too great or too small for the predetermined normal speed of the runner, eddies will be 110

set up and there will be an appreciable loss in efficiency.

An important feature of the invention consists in giving the water-guiding surfaces of the bands profiles which will slope away from the runner axis of rotation at an angle substantially equal to that of the resultant of the vertical and centrifugal forces acting under normal operating conditions upon the 10 water contacting surfaces, that is, the inner surfaces of the bands. This slope is given by the formula

$$15 \quad \tan Q = \frac{Lr_1}{\frac{gH + r_{11}^2 - r_1^2}{w^2} \cdot 2}$$

In this formula

Q =angle of slope.

L =length of the water guiding surface of the runner.

g =acceleration, due to gravity.

H =head of water (in feet) acting on the runner.

w =angular velocity in radians per second at the normal speed.

r_1 =radius in feet of the inlet end of the water-guiding surface of the band.

r_{11} =radius in feet of the outlet end of said surface.

30 By giving the water-guiding surfaces of the bands profiles having slopes substantially as fixed by the formula, the saving becomes very important with runners working at high speeds.

35 It will be understood that r_1 and r_{11} represent the radii of the inlet and outlet ends respectively of the water guiding surface of either the inner band or of the outer band, according to which is being calculated. If

40 the profiles of the water-guiding surfaces of the bands are not straight lines but are curved between the inlet and outlet as may sometimes be desirable then the angle of

slope determined by the formula is the slope of an imaginary line drawn on the profile 45 from the inlet end to the discharge end.

It will be seen that in a hydraulic turbine constructed in accordance with the specific form of the invention where both the inner and the outer band are sloped outward, the 50 water is discharged from the runner in an outwardly sloping direction, rather than in a truly axial direction.

The blades of the runner may be designed both as to number and as to profile at the 55 different sections in any well known way.

It is to be understood that the invention is not to be limited to the particular turbine shown, as it may be embodied in other forms.

What is claimed is:

1. In a hydraulic turbine, a runner having bands formed to provide water-guiding surfaces having profiles sloping away from the axis of the runner in the direction of the water-flow, the angle of the slopes being 60 substantially equal to that of the resultant of the vertical and centrifugal forces acting, under normal operating conditions, upon the water contacting with said surfaces of the bands, substantially as described. 65

70 2. In a hydraulic turbine, a runner having an inner and an outer water-guiding surface, each of said surfaces having such a profile that a line drawn on each profile from the inlet to the discharge end will slope outward away from the axis of the turbine, the tangent of the angle of slope being substantially that given by the formula 75

$$80 \quad \tan Q = \frac{Lr_1}{\frac{gH + r_{11}^2 - r_1^2}{w^2} \cdot 2}$$

substantially as described.

In testimony whereof, I have hereunto set my hand.

JOHN S. CARPENTER.
